DESCRIPTION

U.S. PATENT DOCUMENTS

FIG. 1 is a perspective view of a vehicle light with heating element showing my new design;

D596,323 S * 7/2009 Ishizuka D26/28
D614,330 S * 4/2010 Lamm D26/28
D671,248 S * 11/2012 Fuchigami D26/28
D691,758 S * 10/2013 Lai D26/28
D765,292 S * 8/2016 Liu D26/28
D784,579 S * 4/2017 Cheng D26/28
D794,847 S * 8/2017 Fujiwara D26/28
D806,284 S * 12/2017 Yamaguchi D26/28
D820,484 S * 6/2018 Kamura D26/28
D856,557 S * 8/2019 Lin D26/28

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

In the drawings, the broken lines depict portions of the vehicle light with heating element that form no part of the claimed design.
